Just Walls. Painting a Room? 3 Inexpensive Tools that Make the Job Less Messy. Oct. 26, 2015 [earliest online date], [site visited Apr. 23, 2018]. Available from Internet, <URL:<http://www.justwalls.com/blog/2015/11/3/painting-a-room-3-inexpensive-tools-that-make-the-job-less-messy>>. (Year: 2015).*

Primary Examiner — Eric L Goodman*Assistant Examiner* — Darcey E Heflin(74) *Attorney, Agent, or Firm* — Larson & Larson, P.A.; Frank Liebenow; Justin P. Miller(57) **CLAIM**

The ornamental design for a paint can attachment, as shown and described.

DESCRIPTION

FIG. 1 is a perspective view of a paint can attachment showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines depicting a paint can and handle in FIGS. 1-7 as well as the broken lines depicting a filter bag in FIGS. 1 and 6 depict environmental subject matter only and form no part of the claimed design.
